UNITED STATES PATENT OFFICE.

GEORGE K. COGSWELL, OF DARLOW, KANSAS.

OIL BURNER.

Application filed November 13, 1924. Serial No. 749,643.

My invention relates to oil burners, its object being the provision of an oil burner which is adapted for use in a brooder stove. Such a burner must be simple in construction and operation, it must be capable of responding with extreme sensitiveness to changes in temperature, and its construction must be such that the vapors of combustion can be easily discharged into the air outside the brooder house, that the flame cannot be accidentally extinguished, and that the accidental overflow of the fuel can be conducted to a place of safety. The burner hereinafter described embodies these features.

Referring now to the drawings,

Figure 1 is a median vertical sectional view of my burner.

Figure 2 is a plan view of the burner without the spreader plate and without the covers for the tuyères.

Figure 3 is a plan view of the assembled burner.

Figure 4 is a view in section on the line 4—4 of Figure 3, looking in the direction of the arrow.

The main casting 10 as shown in Figures 1 and 2 is circular in outline and has a bottom and several upstanding ribs integral therewith. At the center is the inlet opening surrounded by the cylindrical rib 11. Concentric with the rib 11 is a second rib 12, the top of which is at a higher level than that of the rib 11. The rib 12 encloses a circular chamber which constitutes the combustion chamber or cup.

A third rib 13 surrounds and is concentric with the ribs 11 and 12. The height of the main portion of the rib 13 is a trifle less than that of the ribs 12, but the rib 13 has a plurality of depressed portions 13^a whose height is only a little more than half the height of the main portion. A fourth rib 14 lies just inside the periphery of the casting 10, the annular flange outside the rib being just wide enough to support the sheet iron wall of the heater. In a radial direction from the depressed portions 13^a of the wall 13, the wall 14 has substantially the same height as that of the portion 13^a, but at other points the wall 14 serves only as a support for the heater casing, and in order to save material and to reduce the weight its height may be reduced to a point consistent with its function.

The casting 10 is also provided with a

plurality of pairs of radial ribs 15 extending from the rib 13 to the rib 14. Between the ribs 15 of each pair the portions 13^a and 14^a of the circular ribs 13 and 14 have substantially the same height, this being somewhat more than half the height of the radial ribs 15. The space between the ribs 15 of each pair constitutes an air passage or tuyère, and to better control the air in its movement these passages are covered by the lids or covers 16. These covers have ribs 16^a on their under side to prevent displacement of the covers.

The flame spreader 17 is circular in outline with a laterally projecting ear 17^a. The ear 17^a is apertured to receive a pivot pin 18, such as a bolt or the like, for pivotally securing the flame spreader to a U-shaped support 19. The support 19 is rigidly secured to the base of the casting 10, preferably in one of the corners formed by the rib 13 with one of the ribs 15. The flame spreader can thus be moved to one side when lighting the burner and then returned to its operative position to direct the course of the flame.

Since the burner is designed primarily for use in brooder houses, it is set up from the floor a sufficient distance to permit the chicks to run around underneath the burner. The legs 20, preferably three in number, (only one of which is shown in Figure 1) are of such length that the chicks have free access to the under side of the burner without at the same time elevating the burner too high for most effectively utilizing the heat. The legs 20 are bolted to the floor of the casting 10, apertures being provided for that purpose in the casting 10.

In assembling the burner the parts above described are positioned as shown in Figure 1 and the furnace or stove wall 21 is bolted to the rib 14, the wall 21 being cut away at the entrances of the tuyères. The oil inlet pipe 22 is connected through the aperture which is at the center of the circular rib 11, being connected to an elevated supply of fuel oil outside the brooder house. Within the space between the circular ribs 12 and 13 there is another aperture 23 for drawing off oil which might overflow. This aperture communicates with a pipe 24 which passes through the wall to the outside of the brooder house. The pipes 22 and 24 both have T-joints in their connections, as shown in Figure 1. If desired, that portion of the

floor between the tuyères may be covered with sand or gravel to equalize the heat.

I prefer to assemble the device with a sight feed thermostatic control in the oil feed pipe 22. I find that better results can be obtained in this manner than could be obtained by regulating the draft. In my burner as described, the draft is automatically regulated by the demands of the flame.

- 10 The air must enter through the tuyères, the lids of which compel the air to move in horizontal paths. As soon as the air passes the walls 13^a its natural buoyancy tends to carry the air upwardly, this tendency being increased by the intense heat at these points.
- 15 The volume of the air coming through the tuyères as well as the inclination of the air currents, varies with the intensity of the heat underneath the flame spreader. The top of the circular rib 12 must be at such a height relative to the air passages that the air currents will strike the top of the rib 12 obliquely and at points above the level of the outlets of the tuyères. I have found
- 20 also that the tuyères must be angularly disposed toward each other since the flame is otherwise certain to be blown out by the currents of air. I have shown three equidistantly spaced tuyères, but it is obvious that the number may be varied at will so long as the staggered arrangement is maintained.

In operation the burner is even more simple than in construction. It is necessary only to swing the spreader cap out of the way, to open the oil valve, and to light the burner. The oil emerges through a quarter-inch pipe, and the flow is certain since there are no small orifices to become carbonized and clogged. The flame is entirely above the top of the rib 12 and appreciably above the oil outlet, thus insuring against all possible danger of backfiring. This danger is still further eliminated by the fact that the fuel reservoir and feed pipe are all in places where the temperatures are considerably below the flashing point of the fuel. The only place in which soot sometimes is formed is in the combustion cup formed by the rib 12, but such soot can be quickly dislodged by means of a piece of wire or a nail, or any other suitable tool which happens to be handy. Such dislodged soot will be quickly consumed after lighting the burner.

- 55 In the very improbable event of an overflow of the oil, the overflowing oil will be

carried away through the pipe 24 to the outside of the brooder house, where any suitable receptacle can be employed to catch the drain. In this way the oil will not be discharged where its fumes might be dangerous to the chicks or where it might be ignited. Neither will it be wasted, since such oil can be collected and transferred to the oil feed tank when filling that receptacle.

I have used the burner for a number of seasons, in all kinds of weather, and through a wide range of temperatures, and I find that the quantity of air which is supplied through the tuyères is always equal to the demands of the flame. When the flame is fed by a heavy flow of oil there is no sooty flame, and when the oil feed is reduced to a very tiny stream, or to merely periodic drops of oil, there is no tendency of the flame to blow out.

Having thus described my invention in terms which will be readily understood by those skilled in the art to which it pertains, what I believe to be new and desire to secure by Letters Patent of the United States is:

An oil burner including a flat circular disc having four concentric upstanding ribs integral therewith, said disc being provided with a centrally positioned aperture for admitting liquid fuel, the innermost of said ribs surrounding the central aperture of said disc to constitute a passageway for the fuel, the second of said ribs having its upper edge at a higher level than that of the said innermost rib and forming therewith a combustion cup, the third of said ribs having a height less than that of the second of said ribs but greater than that of the said innermost rib and forming with said second rib an annular overflow chamber for the fuel, the fourth of said ribs being adjacent the periphery of said disc and having its upper edge at a lower level than that of the second of said ribs, a plurality of pairs of radial ribs integral with and connecting said third and fourth concentric ribs, each pair of said radial ribs forming a tuyère for the passageway of air, said third rib being cut away between the ribs of each pair of said radial ribs, and removable covers for said tuyères, said covers being each adapted to completely cover only one tuyère.

In testimony whereof I affix my signature.

GEO. K. COGSWELL.
